UNITED STATES PATENT OFFICE.

GEORGE R. BAILEY, OF BROOKLYN, NEW YORK, ASSIGNOR TO STERLING CASKET HARD-WARE COMPANY, OF BROOKLYN, NEW YORK, A CORPORATION OF NEW YORK.

DESIGN FOR AN ORNAMENT FOR CASKETS.

50,772.

Specification for Design.

Patented May 15, 1917.

Application filed March 7, 1917. Serial No. 153,199. Term of patent 7 years.

To all whom it may concern:

Be it known that I, GEORGE R. BAILEY, a citizen of the United States, residing at No. 502 Bedford avenue, in the borough of Brooklyn, county of Kings and State of New York, have invented a new, original, and ornamental Design for Ornaments for Caskets, of which the following is a specification, reference being had to the accompanying drawing, forming part thereof.

The figure is a plan view of an ornament for caskets showing my new design.

I claim:

The ornamental design for an ornament for caskets as shown.

GEORGE R. BAILEY.

Witnesses:

A. M. VIKBERG,
VICTOR C. CONNIER.
